UNITED STATES PATENT OFFICE.

PEARLE ROSCOE GAWTHROP, SR., OF ADRIAN, WEST VIRGINIA.

WATER OR MUCK BAILER.

1,401,903.

Specification of Letters Patent. Patented Dec. 27, 1921.

Application filed January 26, 1920. Serial No. 353,975.

To all whom it may concern:

Be it known that PEARLE ROSCOE GAWTHROP, Sr., a citizen of the United States, residing at Adrian, in the county of Upshur 5 and State of West Virginia, has invented certain new and useful Improvements in Water or Muck Bailers, of which the following is a specification.

This invention relates to hand bailers 10 adapted to be used for moving muck, slush and similar material in close places, and it consists in the novel features hereinafter described and claimed.

An object of the invention is to provide 15 a bailer of the character stated which may be used to advantage for moving or removing the material in mines, between railway ties, in boats or other places where the material may be located and where the space for 20 operating or manipulating the bailer is limited.

A further object of the invention is to provide for a bailer as stated, a bowl portion 25 of special design and configuration which is adapted to receive and retain the material while the operator is in the act of scooping it up and casting the same over his head or shoulder, thereby preventing the material from escaping from the bowl while 30 it is being lifted and cast and protecting the operator in his person and clothing from the drippings which otherwise would fall from the bailer and deposit upon him.

With these and other objects in view the 35 bailer comprises a bowl portion, made from sheet metal, and in the general form of a truncated cone, closed at its larger end and open at its smaller end. The sides and top 40 of the bowl are flat or substantially so. The bowl is longer at its top side than at its bottom thereby providing space for the reception of a maximum amount of the material and affording a fulcrum point at the bottom of the bowl whereupon it may be 45 rocked while the material is being gathered therein. A socket member is mounted at the larger end of the bowl and receives the lower portion of a handle. A brace is connected with the intermediate portion of the 50 handle and the top side of the bowl.

In the accompanying drawings:

Figure 1 is a side elevation of the bailer.

Fig. 2 is a top plan view of the same with parts broken away.

Fig. 3 is a front elevation of the bailer.

Fig. 4 is a side elevation of a modified form of the bailer.

As illustrated in the accompanying drawing the bailer comprises a bowl portion 1 having a socket member 2 mounted at the rear end thereof. The end of a handle 3 is inserted in the said socket member and the handle is disposed with its longitudinal dimension pitched at an obtuse angle to the median longitudinal dimension of the bottom of the bowl. A brace 4 is connected at one end with the intermediate portion of the handle and at its other end with the top side of the bowl.

The bowl 1 is made from sheet metal the 70 edges of the sheet being overlapped and secured together forming a seam 5 which is disposed along the median longitudinal dimension of the top side of the bowl. The bowl is in the general form, in side elevation, 75 of a truncated cone having a substantially semi-ovate larger end. The bottom 6 of the bowl is curved or convexed transversely. The sides 7 are flat and the top 8 is flat or substantially so. The bowl is open at its 80 smaller forward end as at 9 and the substantially semi-ovate portion 10 closes the rear end of the bowl and forms the rear side thereof. The portion 10 merges with the rear portion of the bottom 6 at a point 11 85 which is located at a point between the ends of the top side 8 and which may serve as a rocking or fulcrum point for the bowl when the implement is in use and the material is being gathered in the bowl.

By providing a bowl of the shape and design set forth it is apparent that the implement may be used to advantage for taking up the muck or slush in close places and when the bowl is elevated by the operator the 90 said material is retained within the bowl. When the bowl is moved to a position above the head or shoulder of the operator the opening 9 is swung in an upward direction and consequently the material is retained 95 within the bowl until such time as the opening 9, during the movement, is disposed in a downward direction.

In the form of the invention as illustrated in Fig. 4, of the drawing, the top side 8' is 105 joined to the body of the bowl along the lines 9'. In this form of the invention the body of the bowl is made in one part and the top in another part and these parts are placed together and welded, thereby form- 110

ing the bowl and eliminating the seam 5 as shown in Fig. 3 of the drawing.

Having described the invention what is claimed is:—

- 5 A bailer of the class described having an open front end and imperforate top, side bottom and rear end walls, said rear end wall being disposed at an obtuse angle to the bottom wall and merging therewith by a
10 curved surface forming a rocking fulcrum for the bowl, said top wall being inclined at

an acute angle to the rear end wall and joined thereto by the curved wall portion, said top and side walls terminating forwardly in a plane perpendicular to the forward edge of the bottom wall, said top and side walls being joined by curved wall portions whereby the interior of said scoop is free from angles.

15 In testimony whereof I affix my signature. 20

PEARLE ROSCOE GAWTHROP, Sr.
